CLAIM

The ornamental design for a footrest, as shown and described.

DESCRIPTION

FIG. 1 is a perspective view of our new design for a footrest.
FIG. 2 is a front elevation view of the footrest.

FIG. 3 is a rear elevation view of the footrest.

FIG. 4 is a top plan view of the footrest.

FIG. 5 is a bottom plan view of the footrest.

FIG. 6 is a left side elevation view of the footrest; and,

FIG. 7 is a right side elevation view of the footrest.

The broken line portions of the drawings represent environmental structure only and do not form part of the claimed design.
